MULTI PISTON RAM DEVICE

Rowan Herbert Colley, Derby, England, assignor to Rolls-Royce Limited, Derby, England, a British company

Application March 11, 1955, Serial No. 493,701

Claims priority, application Great Britain March 23, 1954

7 Claims. (Cl. 60—97)

This invention relates to ram devices, such for instance as may be used to adjust area-varying means of variable-area jet nozzles provided at the outlet ends of gas-turbine engine exhaust pipes. Variable-area jet nozzles are usually employed when reheat combustion equipment is provided to burn fuel in the exhaust pipe. 15

Such jet nozzles usually comprise a fixed nozzle member which defines the maximum possible effective area of the variable-area nozzle and adjustable nozzle elements which are moved over the orifice of the fixed nozzle member to give a reduced effective area. The adjustable nozzle elements take a number of forms, one well-known form being the eyelid type of adjustable element, of which there are usually two, pivoted substantially about a diameter of the fixed nozzle member, and another form being the finger type, of which there are usually several, projecting beyond the fixed nozzle member and pivoted at their upstream ends about axes which are substantially tangential to the periphery of the fixed nozzle member.

The adjustable nozzle elements are usually actuated by pneumatic rams, since there is a substantial risk of fire if oil-operated rams are employed adjacent the hot exhaust pipe. With a simple pneumatic ram, it is possible to obtain only two positive positions of adjustment, that is, the end positions of the ram piston, since hunting will occur if the piston is restrained from movement from an intermediate position solely by balance of the air pressure loads acting on it. 35

It has become desirable with modern jet propulsion engines fitted with reheat equipment, to provide for several different degrees of reheat, and for each different degree of reheat there is required a corresponding nozzle area.

This invention has for an object to provide an improved ram device suitable for operating the adjustable nozzle elements of a variable-area nozzle, whereby the piston may be positively positioned, in one sense at least of its movement, in more than two positions. The ram device is not, however, limited in its use to the operation of nozzle elements, but may be employed generally when a ram piston is required to be stopped between the ends of its travel.

According to the present invention, a ram device comprises a ram cylinder, at least three pistons within the cylinder and dividing the cylinder into two end spaces and a plurality of intermediate spaces, each intermediate space being between an adjacent pair of the pistons, a pair of spaced abutments on the cylinder, one end piston of said pistons co-operating with said pair of abutments whereby travel of the one end piston relative to the cylinder in each direction is limited, a piston rod connected to the other end piston of said pistons and projecting externally of the ram cylinder, each pair of adjacent pistons having coaxial, nested, telescoping portions comprising an axially extending portion on at least one of the pair of adjacent pistons, a portion having an axial recess on the second piston of the pair, the axially extend-

2

ing portion projecting into the recess, co-operating abutments on said axially extending portion and on the recessed portion respectively limiting relative movement in each direction of the pair of adjacent pistons, and pressure fluid supply means selectively connectible to supply pressure fluid to said intermediate spaces and to at least one of the end spaces.

The other of the end spaces may have pressure air admitted to it either permanently or selectively, or the space may be vented to atmosphere and the first piston have applied to it a force to urge it in one direction of its travel.

The cylinder will have as many pressure air supply connections as there are pressure spaces, and it will be appreciated that the spacing of the ports along the cylinder will depend upon the possible relative movement of a piston with respect to its adjacent piston nearer that which has the stops co-operating with the cylinder. In the case of a ram device having more than two pistons one of the pressure air supplies may be effected centrally, say through the piston rod, and in this way a saving in overall length of the ram device may be obtained.

Two embodiments of ram device according to this invention will now be described with reference to the accompanying drawings in which:

Figure 1 illustrates a four-piston ram device,

Figure 2 illustrates a three-piston ram device shown in the end positions of its travel,

Figures 3 to 6 illustrate four of the intermediate positions obtainable with the ram device of Figure 2,

Figure 7 is a diagrammatic view of one suitable form of air supply for use with the ram of Figures 2 to 6, and

Figures 8 to 11 show various forms for a part of the ram device shown in Figures 2 to 6.

Referring now to Figure 1, there is illustrated a ram comprising a cylinder 10 and four pistons 50, 51, 52 and 53, of which three pistons, viz: pistons 50, 51 and 52, are similar in construction and in which piston 53 is formed with a piston rod 54 carrying the fitting 18.

Each of the pistons 50, 51 and 52 is provided with an axial extension 55 to the right which slides on the piston rod 54 and has a flange 56 at its right hand end, the flange 56 provides the abutment limiting the movement of the respective piston and in the case of the piston 50 co-operates with the end of the cylinder or with a circular spring clip 58 mounted in an axial boss 57 on the end of the cylinder, and which in the case of the pistons 51 and 52 comes up against the piston next to the right of it in one direction and against a circular spring clip 58 carried in an axial hollow boss on the piston to the right of it.

The piston 53 is limited in its movement relative to the piston 52 by a flange 59 on the rod 54, which flange 59 comes up against the piston 52 in one direction of movement of the piston 53 and against a circular spring clip 58 corresponding to the circular spring clips 58 of the other pistons. It will be clear that with this ram device sixteen positions of the fitting 18 relative to the cylinder 10 are obtainable.

From the foregoing description it will be appreciated that the invention provides a simple form of ram device with which more than two positions are obtainable and in which the piston is positively held against movement in one direction.

Referring now to Figure 2, the ram device illustrated comprises three pistons, 60, 61 and 62 of which piston 60 is carried on a piston rod 63 which at its right hand end passes through a seal carried in the cylinder 10 and carries the end fitting 18 and has also a portion 63a extending to the left and entered into a tubular member 65 which carries the piston 61. A circumferentially and radially extending projection 64 is formed at the end of portion 63a

and serves to limit the movement of the piston 60 relative to the piston 61, the projection 64 co-operating with either the stop at the right hand end of the tubular member 65 provided by a conical spring retaining ring 66 entered into an annular groove internally of the tubular member 65 or the closed left hand end 67 of the tubular member 65. At its right hand end the tubular member 65 has a radially and circumferentially extending portion 65a which bears against the inside surface of the cylinder 10 and acts as a guide for the piston 61. The tubular member 65 is also extended to the left and enters into a second tubular member 68 which carries the third piston 62. The left hand end of the tubular member 65 carries a radially and circumferentially extending projection 69 which co-operates with either a second conical spring retaining ring 71 or the left hand closed end 70 of the second tubular member 68 and serves to limit movement of the second piston 61 relative to the third piston 62. The second tubular member 68 is also extended to the left and carries a radially and circumferentially extending projection 72 which limits the travel of piston 62 in the cylinder by abutting against either the end wall 10a of the cylinder or against a third conical spring retaining ring 73.

The three pistons 60, 61 and 62 divide the cylinder into two end spaces 74 and 75 and two intermediate spaces 76 and 77, space 76 being between pistons 60 and 61 and space 77 being between pistons 61 and 62. Four ports 78, 79, 80 and 81 are provided on the cylinder, port 78 communicating with end space 74, port 79 with intermediate space 76, port 80 with intermediate space 77 and port 81 with end space 75. Pressure air is supplied through port 78 permanently to the end space 74 to exert a force on piston 60 acting towards the left. Pressure air is supplied selectively to the other three spaces 76, 77 and 75 through the ports 79, 80 and 81 by means of solenoid-controlled valves.

A hole 82 is provided in the tubular member 65 and a hole 83 is provided in the projection 64 at the end of portion 63a of rod 63 to allow passage of pressure air from port 79 to all parts of space 76. Holes 84 and 85 are provided in the left-hand end of tubular member 65 and the left-hand end of tubular member 68 respectively, the hole 84 being provided to allow pressure air from port 80 to gain access to all parts of space 77 and the hole 85 being provided to allow pressure air from port 81 to gain access to all parts of space 75.

This construction of ram is fully double-acting in all positions, as due to the space 74 being permanently supplied with pressure air the piston 60 is biased to move to the left by a force equal to the annular area of the piston 60 multiplied by the air pressure but, due to the fact that pressure air supplied to any of the other spaces 76, 77, 75 acts on an area equal to the full area of the piston, the force tending to move piston 60 to the left will be overcome and there will be a resultant force moving piston 60 to the right equal to the air pressure multiplied by the cross-sectional area of the piston rod 63. Thus if there is no pressure air in the end space 75 and the two intermediate spaces 76, 77 then the piston 60 will move to the left to the limit of its travel, portion 64 abutting against the closed end 67 of the first tubular member 65, portion 69 abutting against the closed end 70 of the second tubular member 68 and portion 72 abutting against the end 10a of the cylinder 10. If pressure air is supplied to all the spaces then the ram will take up the position shown in the bottom part of Figure 2, portion 64 abutting against the first conical spring retaining ring 66, portion 69 abutting against the second conical spring retaining ring 71 and portion 72 abutting against the third conical spring retaining ring 73. Figures 3 to 6 illustrate four of the intermediate positions obtainable with the ram, the position of Figure 3 being obtained by supplying pressure air to end space 75 and intermediate space 77, with intermediate space 76 vented to atmosphere, the position of Figure 4 being

obtained by venting end space 75 and intermediate space 77 to atmosphere and supplying pressure air to space 76, the position of Figure 5 being obtained by supplying pressure air to end space 75 and intermediate space 76 with space 77 vented to atmosphere, and the position of Figure 6 being obtained by venting end space 75 to atmosphere and supplying pressure air to both intermediate spaces.

Referring now to Figure 7, there is shown one suitable form of air supply means for use with the ram just described.

The control comprises an air compressor 100 which has a suction pipe 101 connected to any convenient air source, for instance the delivery of a compressor of a gas turbine engine with which the ram device is associated, a relief valve 102 connecting the delivery pipe 107 of compressor 100 to one end of a return pipe 103, the other end of which is connected to the suction pipe 101, air cleaners 104, 105 for removing entrained oil and water respectively, a pressure air reservoir 106, and a control valve assembly 108 joining the delivery pipe 107 to branch pipes 109, 110, 111, 112 leading respectively to ports 78, 79, 80 and 81 of the ram device.

The connection between delivery pipe 107 and branch 25 109 is a direct connection, but each of the other branches 110, 111, 112 has a respective solenoid-operated valve 113, which, when the solenoid 114 is de-energized, is urged by a spring 115 to close a port 116 to disconnect the branch to a vent 117 through port 118, and which, 30 when the solenoid 114 is energized, is moved away from port 116 and closes off port 118. The solenoids 114 are supplied with operating current from the aircraft battery 120 through throttle-controlled switches 119.

The parts 66, 71 and 73 which form abutments may be 35 30 of any convenient form.

Referring now to Figure 8, there is illustrated one form which the parts 66, 71 and 73 may take. The ring is of parallelogram axial section, and the outer surface 90a, which is thus frusto-conical, is arranged to 40 fit against the surface 91a of the groove in the part 92. The inner surface 90b of the ring is likewise frusto-conical and is parallel to the surface 90a. One end face 90c is contained in a plane at right angles to the axis and seats against the surface 91b of the groove in the part 92, and the other end face 90d of the ring is also contained in a plane at right angles to the axis and projects 45 wholly within the bore of the part 92 and forms an abutment surface for engagement by the part 93 to limit the movement of the part 93 relative to the part 92 in one direction. It will be seen that in this case the surface 93a of the part 93 which comes up against the end face 90d is contained in a plane at right angles to the axis, and it will be seen moreover that the abutment 50 surface provided by the end face 90d extends through the full thickness of the ring 90. Also it will be seen that axial loads on the ring 90 are transmitted to the part 92 over the full radial thickness of the ring.

Referring now to Figure 9, there is shown an alternative and preferred arrangement, and in this case the surface 91b of the groove is also frusto-conical and has its 60 generatrix at right angles to the generatrix of the surface 91a. The ring 90 in this case is of rectangular section so that the end faces of the ring 90c, 90d are also frusto-conical. The part 93 is arranged to bear on the abutment ring 90 through a surface 93b which is also frusto-conical, the part 93 being chamfered to obtain this surface. It 65 will be seen with this arrangement that the loads on the ring 90 are purely compressive loads and that the lines of action of the resultant loads on the end faces 90c, 90d of the ring 90 are the same. This line of action is indicated by a chain line 94.

Referring now to Figure 10, there are indicated a number of other features.

It will be seen that the ring 90 is of such axial length 70 that its outer surface 90a has its minimum diameter por-

tion projecting from the groove in the part 92 and that the part 93 has a peripheral rebate 93c adjacent the chamfered surface 93b. The adoption of this feature avoids a difficulty which may otherwise occur when the parts 92 and 93 are relatively movable parts due to peening over of the ring 90 and peening of the outer diameter of the part 93 which may be caused by hammering of the part 93 on the ring 90. By provision of the peripheral rebate 93c any increase in the diameter of the part 93 adjacent the junction between the rebate 93c and the chamfer 93b does not cause an increase in the overall maximum diameter of the part 93 and thus jamming is avoided.

The ring 90 may be removed from its groove in a number of ways. For instance, an annular tool of a section such as is shown at 95 to the left of the figure may be inserted into the part 92, and in this case the ring is pushed out of the part 92 to the right. Alternatively a number of radial holes 96 may be provided around the part 92 for the insertion of pins by which the ring 90 may be pushed out of its groove. Alternatively a number of pockets 97, say three, may be provided in the bore of the part 92 to extend into the ring groove and a clawed tool employed to enter the pockets and to pull the ring 90 from the groove by bearing on the surface 90c.

Referring now to Figure 11, there is shown an arrangement in which the stop ring 90 is accommodated in a groove formed externally of the part 93 for abutment by the part 92.

I claim:

1. A ram device comprising a ram cylinder, at least three pistons within the cylinder and dividing the cylinder into two end spaces and a plurality of intermediate spaces, each intermediate space being between an adjacent pair of the pistons, a pair of spaced abutments on the cylinder, one end piston of said pistons co-operating with said pair of abutments whereby travel of the one end piston relative to the cylinder in each direction is limited, a piston rod connected to the other end piston of said pistons and projecting externally of the ram cylinder, each pair of adjacent pistons having coaxial, nested, telescoping portions comprising an axially extending portion on at least one of the pair of adjacent pistons, a portion having an axial recess on the second piston of the pair, the axially extending portion projecting into the recess, co-operating abutments on said axially extending portion and on the recessed portion respectively limiting relative movement in each direction of the pair of adjacent pistons, and pressure fluid supply means selectively connectible to supply pressure fluid to said intermediate spaces and to at least one of the end spaces.

2. A ram device as claimed in claim 1, having four pistons, whereof three accommodated wholly in the cylinder are hollow and slide in the cylinder between abutments thereon and the others slide in the next adjacent piston between abutments thereon, and whereof the fourth has a piston rod extending outside the cylinder and sliding in one of said three pistons, said rod being connected to a part to be moved by the ram device.

3. A ram device comprising a ram cylinder, first and second end pistons and a third piston between the end pistons, the pistons sliding within the cylinder and dividing the cylinder into two end spaces and two intermediate pressure spaces, a first hollow piston rod on the first end piston, the hollow piston rod being wholly within the cylinder, co-operating abutment means carried by the hollow piston rod and the cylinder respectively and limiting relative movement of the first end piston within the cylinder, the third piston having an effective area equal to the effective area of the first end piston, said first end piston having a portion with an axial recess therein and the third piston having an axially-extending portion projecting in the recess, co-operating abutments on the recessed portion and the axially-extending portion respectively limiting relative movement of the first end piston and the third piston, a piston rod carried by the second end piston and projecting through the adjacent end space to externally of the cylinder whereby the second end piston has a first surface of effective area equal to the effective area of each of the other pistons and a second surface facing the adjacent end space of less effective area than the first surface, said third piston having a portion with an axial recess and the second end piston having an axially-extending portion projecting within the recess of said portion of the third piston, co-operating abutments carried by the recessed portion of the third piston and by the axially-extending portion of the second end piston respectively limiting relative movement of the third piston and second end piston, and pressure fluid supply means operable to be connected selectively to the intermediate spaces and at least one of the end spaces.

4. A ram device according to claim 3, wherein the other end space has an outlet connected to atmosphere.

5. A ram device according to claim 3, wherein the other end space has an outlet permanently connected to the pressure fluid supply means.

6. A ram device according to claim 3, wherein the other end space has an outlet selectively connectible to the pressure fluid supply means.

7. A ram device as claimed in claim 3, wherein some at least of said abutments for said pistons are provided by rings received in grooves in the cylinder or adjacent pistons, and the pistons are provided with radial projections to co-operate in abutment with the rings.
